[57] **CLAIM**

The ornamental design for a lighted bag, as shown and described.

DESCRIPTION

FIG. 1 is a front, top and side perspective view of the lighted bag showing my new design in the open condition, with the interior side opposite to that shown being identical to the side shown;

FIG. 2 is a front elevational view thereof, the rear being a mirror image of the front shown in FIG. 2;

FIG. 3 is an end elevational view thereof, the end opposite being a mirror image of the end shown in FIG. 3;

FIG. 4 is a top plan view thereof; and,

FIG. 5 is a bottom plan view thereof.
